CASEMENT WINDOW

David R. Canny, Los Angeles, Calif.

Application November 14, 1932, Serial No. 642,503

3 Claims. (Cl. 16—160)

This invention relates generally to casement window construction, more specifically to means for operating the sashes, and is an improvement over my prior U.S. Patent No. 1,621,828, issued

March 22, 1927.

Heretofore, considerable trouble has been experienced with the usual casement windows due to leakage during rainy weather and from flapping of the sashes when opened.

It is therefore an object of the present invention to provide a sash operating mechanism constructed in such a manner that a leak-proof joint may be secured between the sash and frame when in closed position.

Another object is to provide a device of the character referred to whereby one or both of the sashes may be retained or locked in partially open position.

A further object is to provide a sash construction in which the sashes may be locked in closed position without the use of hooks, bolts or other extraneous fastening devices.

Other objects and advantages will be apparent from the following description, reference being had to the accompanying drawings, in which:

Fig. 1 is a front elevation of the improved casement window construction with sashes shown in closed position, parts being broken away and shown in section.

Fig. 2 is a horizontal section taken on the line 2—2 of Fig. 1.

Fig. 3 is a view similar to Fig. 1 showing one sash disengaged from the other prior to opening the same.

Fig. 4 is a vertical section taken on the line 4—4 of Fig. 1.

Fig. 5 is a view similar to Fig. 1 showing one sash in partially open position.

Fig. 6 is a vertical section taken on line 6—6 of Fig. 5.

Fig. 7 is a horizontal section taken on line 7—7 of Fig. 5.

Figs. 8 and 9 are enlarged fragmentary front elevations of the sash, jamb and operating mechanism, the sash being shown in closed position corresponding to Fig. 1.

Figs. 10 and 11 are views similar to Figs. 8 and 9 but showing the sash in released position.

Fig. 12 is an elevation of the actual sash operating mechanism removed from the sash and looking toward the inner face thereof.

Fig. 13 is a section taken on line 13—13 of Fig. 12.

Fig. 14 is a section taken on line 14—14 of Fig. 12.

Fig. 15 is an inner face view of the upper or complementary sash operating mechanism.

Fig. 16 is a section taken on line 16—16 of Fig. 15.

Referring more specifically to the drawings, Fig. 10 designates the frame of the improved casement window construction and consists of the usual top rail 11, sill 12 and side rails or jambs 13.

Formed in top rail 11 is a pair of ledges 14 in offset relation, in each side rail a groove or channel 15, and in the sill a ledge 16, all of which contact with the window sashes designated at 18 to form a weather-proof joint when the same are in closed position.

Secured to the side rails 11 of frame 10 and hingedly connected to side bars 18a of sashes 18 adjacent each end thereof are operating mechanisms designated at 20 and 21 respectively which serve to lock the sashes in closed position, disengage the same (prior to opening), to permit swinging movement in the usual manner, or lock them in partially open position.

Sash operating mechanism 20 cooperates with mechanism 21 to simultaneously lift and shift the sashes laterally. The latter device, however, serves to effect such movement and is preferably connected to the lower portion of the sash and frame so that it will be easily accessible, especially so when applied to windows.

Mechanism 21 consists of a plate 22 that is slidably mounted on block 24, the block being provided with lateral flanges 25 (see Fig. 13) that engage recesses 26 formed in guide members 23 secured to the plate. Plate 22 is preferably of square shape and is provided with a flange 22a which serves to enclose the above parts.

Pivotedly mounted on a stud 27 projecting from plate 22 is a lever 28, which serves to shift plate 22 on the block 24. Secured to lever 28 is a pin 29 that projects into a slot or recess 30 formed in block 24, there being an arcuate slot 31 formed in plate 22 to accommodate movement of said pin.

Block 24 is secured by screws or the like 32 to one flange of an angle bracket 34, the other flange 35 of which is adapted to be rigidly secured to the inner face of the side rails of frame 10. Hingedly connected to plate 22 as indicated at 36 is a leaf 37, which is adapted to be secured to the outer side bars 18a of the sashes, said leaf being bent as indicated at 38 to facilitate such connection.

Mechanism 20 consists of a plate 40 that is hingedly connected as indicated at 41 to a leaf 42 which is adapted to be secured to the side bar 18a of the sash.

Secured to plate 40 are guide members 43 that slidably engage a block 44 which is pivotally connected as indicated at 45 to an angle bracket 46, the flange 47 of which is adapted to be connected by screws or the like to the inner side face of rail 11 of window frame 10.

The opposite end faces of the bracket are formed on a radius described from the axis of pivotal connection 45 as indicated at 48 in order to permit adjustment between the plate and frame during assembling and to compensate for any distortion of the sash or frame which may occur after installation, i. e. so that the plate will slide freely on the block.

15 It will be apparent that due to blocks 24 and 44 being disposed at an angle when in assembled relation in the frame as shown, the window sashes will travel in a diagonal path upon operation of mechanisms 21 to lock or disengage the same.

20 When the sashes are in closed or locked position the tongues and grooves 18b interlock, the lower bars 18c rest on the sill, the side bars 18a extend into the grooves 15, and the flanges 18d formed on the upper cross members overlap the ledges 14 formed in the upper rail of the frame as shown in Figs. 1, 2 and 4. Hence it will be apparent that a substantially leak-proof seal is then formed, also that the sashes cannot be opened from the outside.

25 It will be noted that sufficient clearance is allowed between top and side edges of the sash and grooves formed in the frame (when in closed position) to permit upward and lateral movement of the sashes.

30 When it is desired to open one of the sashes the lever 28 of mechanism 21 is given one-half turn in the direction indicated by the arrow A, the action of which through contact of pin 29 with the lower edge of the slot 30 in block 24 (which is held against movement) disengages one sash from the other as shown in Fig. 3. During such movement plate 34 of mechanism 21 will have been moved upwardly and outwardly on block 24 while plate 40 of device 20 will in like manner move on block 41, as shown in Figs. 10 and 11.

35 It will be noted that due to relative positions then assumed by pins 29 and blocks 24, the sashes will be retained or held in disengaged position. In other words, they cannot return to locked position by gravity until the lever is turned in the opposite direction.

40 When thus disengaged, the lower end faces

of the sashes will be clear of the window sill while their side bars will occupy the channels 15 formed in side rails of the frame.

45 It will be noted that the outer end faces of the side bars 18 and inner faces of the channels 15 are slightly beveled in order to permit opening of the sashes.

50 After manipulating the levers 28 of members 21 in the manner above described, either or both of the sashes may be opened in the usual manner, as indicated by dotted lines in Fig. 7.

55 By turning lever 28 upwardly after opening the sash the same may be locked in partially open position as shown in Fig. 7.

60 From the foregoing it will be seen that the improved casement window construction may be quickly installed and very efficiently serves its intended purpose.

I claim:

65 1. A sash operating mechanism comprising a bracket, a block having a slot formed therein secured to said bracket, a plate slidably mounted on said block, a leaf hingedly connected to said plate, and a lever provided with a pin pivotally mounted on said plate with the pin thereon extending into the slot in said block, whereby on turning of the lever said plate may be simultaneously shifted vertically and laterally on said bracket.

70 2. A sash operating mechanism comprising a bracket, a block having a slot formed therein secured to said bracket, a plate slidably mounted on said block, a leaf hingedly connected to said plate, diagonally disposed guide means secured to said plate and engaging said block, and a lever provided with a pin pivotally mounted on said plate with the pin thereon extending into the slot in said block, whereby on turning of the lever said plate may be simultaneously shifted vertically and laterally on said bracket.

75 3. A sash operating mechanism comprising a bracket, a block having a slot formed therein secured to said bracket, a plate having an arcuate slot formed therein slidably mounted on said block, a leaf hingedly connected to said plate, and a lever pivotally mounted on said plate and having a pin thereon extending through the slot therein into the slot in the block on said bracket, whereby on turning of the lever said plate may be simultaneously shifted vertically and laterally on said bracket.

80 DAVID R. CANNY.
